UNITED STATES PATENT OFFICE.

NICHOLAS A. McMANUS, OF NEW YORK, N. Y., ASSIGNOR TO ITHACA WALL PAPER MILLS, A CORPORATION OF NEW YORK.

DESIGN FOR WALL-PAPER.

SPECIFICATION forming part of Design No. 35,737, dated February 11, 1902.

Application filed January 4, 1902. Serial No. 88,474. Term of patent 8½ years.

To all whom it may concern:

Be it known that I, NICHOLAS A. McMANUS, a citizen of the United States, residing at New York city, in the county of Richmond and State of New York, have invented and produced a new and original Design for Wall-Paper, of which the following is a full, clear, and exact specification, reference being had to the accompanying drawing, forming part thereof.

As shown in the drawing, the leading or material feature of my design consists of the panels arranged in vertical rows, the panels of alternate rows being supported by vertical columns. Each panel consists of the central fleur-de-lis 1, the bunches of flowers 2, and the surrounding scrollwork 3. Each vertical supporting-column consists of the central

stem 4, connecting an upper and a lower panel, and of lines of flowers 5, extending parallel with the stem. Festoons of flowers 6 connect the panels.

This design is particularly adapted for wall-paper for covering side walls.

Having thus described my invention, I declare that what I claim as new, and desire to secure by Letters Patent, is—

The design for wall-paper herein shown and described.

In testimony whereof I affix my signature in presence of two witnesses.

NICHOLAS A. McMANUS.
